UNITED STATES PATENT OFFICE.

EUGENE A. BOURQUIN, OF NEW YORK, N. Y., (EMILY A. BOURQUIN, ADMINISTRATRIX OF SAID BOURQUIN, DECEASED.)

CORN-HUSKING MACHINE.

SPECIFICATION forming part of Letters Patent No. 244,177, dated July 12, 1881.

Application filed May 4, 1880. (No model.)

To all whom it may concern:

Be it known that I, EUGENE A. BOURQUIN, of the city and State of New York, have invented an Improvement in Corn-Husking Machines, 5 of which the following is a specification.

Corn-husking machines have been made in which two pairs of husking-rollers have been supported in a frame and revolved by gearing; but the rollers have to be small in diameter 10 to operate to advantage on the husk; but the gear-wheels that connect such rollers, being also small, are liable to be broken and the teeth do not work properly, especially when one roller separates from the other to let the bunch of husks pass through. These inclined 15 husking-rollers have also been supported in movable journals, so as to yield; but these journals are liable to become clogged with dust and not to slide, hence the rolls are either injured or become inoperative.

My invention is an improvement upon the corn-huskers of the character aforesaid, and relates to a movable frame that carries the husking-rollers, and can be raised or lowered 25 at one end, so as to vary the angle at which the rollers stand, and cause the ears of corn to move with greater or less rapidity as they slide down; also to the arrangement of the gearing, whereby larger gear-wheels can be 30 used without increasing the size of the rollers, and the gear-teeth always interlock correctly; also to the construction of the yielding bearings for one roller in each pair to insure rapidity of opening and closing movement; also 35 to the feed-apron and adjusting mechanism to vary the inclination of the ear as it reaches the husking-rollers.

In the drawings, Figure 1 is a vertical section of the machine. Fig. 2 is a sectional plan 40 at the line $x-x$. Fig. 3 is a cross-section of the rollers at the line $y-y$; and Fig. 4 is a section at the line $z-z$, Fig. 3.

The main frame of the machine is preferably 45 of wood, with standards a , rails b , and cross-bearers b' . The main shaft c is in bearings c' upon this frame, and the same may be driven by a belt to the pulley d , or a fly-wheel, d' , and a crank-handle can be used to give motion to the machine. I have represented by dotted lines 50 in Fig. 1 a lever, e , pivoted to the frame, and

a link, e' , connecting the lever to a crank-pin upon the fly-wheel.

The auxiliary metal frame $f f'$ is between the wooden side frames. At its upper end it is hooked over tubular extensions from the bearings c' , through which tubular extensions the shaft c passes, so that the lower end of the frame $f f'$ can be raised or lowered without altering the position of the gearing that is carried by the frame $f f'$ in its relation to the 60 driving-wheel g upon said shaft c .

The lower end of the frame $f f'$ is provided with segmental slots for the clamping-bolts h , and the adjusting-screw h' and wheel-nut 3 , that is above the cross-bar 4 , serve to support 65 and adjust the position of the frame $f f'$ and the parts carried by it, while the clamping-bolts h' are loose.

The frame $f f'$ carries two pairs of husking-rollers, the rollers $l l$, near the center, being in 70 stationary bearings $6 6$ on the cross-bar f' of said frame f , and the rollers $n n$, near the outer parts of the cross-bar f' , being in movable bearings.

I am aware that rollers arranged in pairs 75 and at an inclination have been used, and that the bearings for the outer rollers have been movable; but as these rollers revolve very fast, and frequently draw off bunches of husks, the rollers, or the rubber blocks of the rollers, are 80 injured, because the sliding bearings do not yield with freedom and rapidity. To avoid this difficulty, and also to prevent the bearings becoming wedged apart, I make use of swing-lever-bearings $o o$. Each bearing is double, 85 so as to straddle the cross-bar f' of the frame f , one leg or lever passing at each side of the frame, the bearing o , for the shaft of the roller n , being at the upper part, and a spring acting upon the lower ends of the levers to press the 90 roller n toward the roller l . The lever-bearings swing on the pivot-pins or bolts r , that pass through the frame and through both the lever-legs of the bearing, and a toe on one of the levers of each bearing, coming against a stop-screw s , limits the movement of the rollers n toward the rollers l , and prevents unnecessary wear upon the rubber blocks that project from the surfaces of the rollers.

I prefer to use the spring-bars t , that pass 100

through adjusting screw-eyes 8, and are provided at their ends with tubes 9, containing rubber tubes, into which rubber tubes the ends of the spring-bars t pass. The tubes 9 bear 5 against the lower ends of the lever-legs of the bearings o , and by this construction the bearing is free to swing with little or no friction, and the tube 9 forms a bearing against both legs of the bearing, and the rubber between 10 the tube and the spring-bar forms a cushion that increases the yielding character of the parts. At the same time the necessary force can be applied to the moving roller by adjusting the screw-eye 8 at the center of the spring-bar.

The pieces 12, 13, and 14 form guiding-troughs for the ears of corn as before used.

The shafts of the rollers l , at their upper ends, carry two bevel-gear wheels t^2 , between 20 which the bevel-gear wheel g on the shaft e runs and gives motion to such rollers.

The gears u upon the shafts of the rollers l gear to the wheels v , that are upon gudgeons projecting from the end of the frame f' , and 25 these wheels v gear to other wheels, v' , that, in turn, drive the wheels 16 on the shafts of the rollers n . In consequence of this arrangement the rollers n are free to swing and open and close without the gear-teeth becoming separated, because the gears v' are upon prolongations of the bolts r , that form the pivots for 30 the lever-bearings o , and by making the gears v of double thickness I am able to use larger gears than heretofore, because the gears u and 35 16 lap past each other, instead of gearing together as heretofore.

The cover w serves to hold the ears and prevent their turning up endwise between the husking-rollers. This has before been used.

The feed-apron z' is pivoted, near its upper 40 end, to the screws 18, that pass through the upper ends of the frame f , and there are nuts on said screws, by means of which the upper end of the apron is raised or lowered, so as to 45 determine the angle at which the ear of corn shall pass down the apron and be taken by the husking-rollers. This hinged apron can be swung back out of the way when the gearing is to be cleaned or the parts oiled.

If the bevel-gears t^2 are clamped to the shafts 50 of the rollers l , one pair of husking-rollers can be disconnected, so as to remain stationary, by moving the bevel-gear t^2 back upon the shaft out of gear with the wheel g . If only one 55 bevel-gear t^2 is provided, instead of two, it will be necessary to gear the two middle shafts together by parallel gears, in either instance the gearing of the rollers together in pairs remaining the same. In consequence of arranging the 60 gears in the manner shown I am able to drive all the rollers in the proper direction, and at the same time the middle rollers are not close together, as has heretofore been usual; but they are at a sufficient distance apart to run 65 entirely independently, and hence there will not be any contact of the surfaces of these rollers or of the rubber plugs that may project

from them, and one pair of rollers may remain stationary while the other is in operation, thus adapting the machine to either hand or steam power.

I am aware that in corn-husking machines the outer rollers of the pairs of rollers have been supported in yielding bearings, but these slide upon the cross-bars and speedily become clogged by dust and dirt.

I am also aware that in some kinds of machines rollers have been supported in swinging bearings.

With corn-husking machines it is necessary 80 that the roller-bearings yield with rapidity in passing the lumps of husks, otherwise the rollers are injured.

My yielding lever-bearings are peculiarly constructed, so as to yield freely and at the same time support the rollers firmly and prevent end motion.

I claim as my invention—

1. The combination, in a corn-husking machine, of two pairs of husking-rollers, the frame $f f'$, the driving-shaft and gearing connecting to the rollers, the tubular bearings o' , to which the frame $f f'$ is connected, and through which the driving-shaft passes, and the segmental slots and screws at the lower ends of the frame, 95 as set forth.

2. The frame $f f'$, with the pairs of corn-husking rollers, in combination with the tubular bearings o' , shaft e , adjusting-screw h' , and nut 3, and the clamping-screws h passing 100 through segmental slots in the frame f , as set forth.

3. The combination, with the husking-rollers $l n$ and frame, of the lever-bearings o , made double to straddle the frame, the pivot-bolts 105 r , and the springs acting upon the lever-bearings, as and for the purposes set forth.

4. The combination, with the husking-rollers $l n$, of the lever-bearings o , straddling the cross-bar f' and having toes, and the adjusting-screws s , to regulate the approach of the roller n to the roller l , and springs t , acting upon such lever-bearings, substantially as set forth.

5. The bar-springs t and the adjusting-screw 115 8, in combination with the metal and rubber tubes at the ends, into which the ends of the springs pass, and the lever-bearings o and roller n , substantially as set forth.

6. The combination, with the pairs of rollers $l n$ in a corn-husking machine, of the bevel-gears t^2 on the shafts of the rollers l , and the double bevel-wheel g upon the driving-shaft e , which bevel-wheel passes in between the gears t^2 and drives them, as set forth.

7. In a corn-husking machine, the two pairs of corn-husking rollers and the lever-bearings $o o'$, in combination with the gears u, v, v' , and 116 16, applied to each pair of rollers and arranged and acting as set forth, so that the gears u and 16 16 lap past each other and the gear v' is upon the fulcrum of the lever-bearing of the roller n , substantially as set forth.

8. The combination, in a corn-husking ma-

chine, of two pairs of rollers and the gearing for connecting the respective pairs of rollers, the gear-wheel g and bevel-gears t^2 upon the shafts of the rollers t , substantially as set forth, so that one pair of rollers may be thrown out of action by disconnecting one of the gears t^2 , as specified.

9. The combination, with the corn-husking rollers and their frame ff' , of the feed-apron

z , the hinges or pivots at its upper end, and 10 the adjusting-screws passing into the frame f f' , for the purposes set forth.

Signed by me this 30th day of April, A.D. 1880.

EUGENE A. BOURQUIN.
